UNITED STATES PATENT OFFICE.

FRANCIS J. DOWLING, OF NEW YORK, N. Y., ASSIGNOR TO SEGAL LOCK & HARDWARE CO., INC., OF NEW YORK, N. Y., A CORPORATION OF NEW YORK.

EXPANSIBLE BOLT LOCK.

Application filed June 13, 1925. Serial No. 36,815.

This invention relates to jimmy-proof locks, and more particularly to novel actuating means arranged for use in connection therewith.

5 Among the objects of this invention is to provide a jimmy-proof lock having novel actuating means for operating the bolt, said actuating means having engagement with a relatively fixed abutment member within the 10 lock casing for holding the bolt in retracted or projected position.

Another object of this invention is to provide a jimmy-proof lock or the like having novel actuating means for operating the bolt, 15 said actuating means being arranged for a straight line motion parallel to the axis of the lock, and having a movable member which has co-operation with relatively fixed abutment means for retaining the bolt in retracted 20 or projected position.

Another object of this invention is to provide a lock having a bolt arranged for swinging into the jamb piece laterally of the lock, said lock having actuating means for operating the bolt into projected or retracted position and having a bearing member for this purpose upon which said bolt is arranged to swing, said actuating means comprising a movable member spaced from said bearing member and having engagement with abutment means for limiting the movement of said actuating means and consequently of said bolt when the same has reached its limits of movement.

35 Still another object of this invention is to provide a bolt which is re-enforced by a hardened pin or the like to prevent the same from being sawed through.

With the foregoing and other objects in view the invention consists in the combination and arrangement of parts hereinafter described and claimed, and while the invention is not restricted to the exact details of construction disclosed or suggested herein, 45 still for the purpose of illustrating a practical embodiment of the invention reference is had to the accompanying drawings in which like reference characters designate the same parts in the several views, and in 50 which—

Figure 1 is a longitudinal section of the lock taken on the line 1—1 of Fig. 2.

Fig. 2 is a plan view of the lock mechanism on the line 2—2 of Fig. 1.

Fig. 3 is a section on the line 3—3 of Fig. 55 1 but with the crank member shown in engaging position.

Fig. 4 is a perspective view of a portion of the actuating means.

Fig. 5 is a perspective view of a detail of 60 the actuating means.

Fig. 6 is a fractional view of the lock showing the bolt in retracted position.

In the drawings, a casing 10 is shown mounted upon a door 11, and a keeper 12 65 mounted upon a jamb 13. The lock is provided with a knob 14 for operating the lock from within, and with a plate or keyway 15 without the door through which a key is inserted in a conventional manner. However, 70 with slight changes in construction the lock may be arranged as a mortise lock, and may be used for either sliding or swinging doors.

A bolt 16 is provided which is movable out of the lock casing into the jamb piece, 75 novel actuating means being provided for this purpose which are movable in a direction substantially parallel to the longitudinal axis of the lock or path of movement of the bolt. To render the lock jimmy-proof, the 80 bolt is arranged for movement into the jamb piece in a direction laterally of the lock, a bearing 17 being provided which is carried directly by the actuating means. Said actuating means comprises a plate or carrier 18 85 which is arranged for sliding movement within the lock casing and with which said bearing member may be formed integrally as by means of the neck or extension 19, whereby said bearing member is projected 90 without the lock casing and into the jamb piece when the door is locked. By providing a pair of the bolts 16, I arrange the same for co-operation with each other and to be carried as a unit by the bearing member 17. 95 More specifically, each bolt comprises a pair of arms disposed at an obtuse angle to each other and positioned symmetrically with respect to each other so that when the arms which are at one side of the bearing and within 100 the lock casing lie in contact with each other, the other arms lie without the lock casing and in spaced angular relation. Each bolt is formed with a cut out 20 to receive the neck 19 when the bolt is projected as shown 105 in Figs. 1 and 2. The sides of the opening in the lock casing through which the bolts are projected form cam members 21, so that

when said bolts are retracted, said cam members will bear upon the spaced arms of the bolts and cause the bolts to tilt upon said bearing member, bringing the aforesaid arms into contiguity to each other as shown in Fig. 6. Again, when the bolts are projected, the lugs 22 prevent further outward movement of the bolts by abutting against the wall of the lock casing adjacent to the cams 5. Abutment members 23 are also provided to contact said lugs and to resist a force transversely to said longitudinal axis which may be exerted by a tool inserted between the jamb piece and the lock casing with the object of jimmying the lock. Guides 24 are also provided at the sides of the lock casing each of which contacts a heel or lug 22 to insure of the proper positioning of the bolts with respect to each other when retracted 10 into the lock, and for proper contact between the bearing member 17 and the open bearings provided upon the bolt members. The direction of travel of the bearing member 17 is solely along the longitudinal axis of the lock, thus imparting to the bolts a force whose direction is uniformly constant, the swinging of the bolts being caused in any suitable manner, or by means extrinsic of the actuating 15 means as described.

30 The carrier 18 is movable in co-operation with suitable guide means, such as the lugs 25 at the sides of the lock, with which said plate has sliding contact. Said carrier is also provided with guide means such as the feet 26 which have sliding contact with a wall of the lock to support the rear end of the carrier plate. Said carrier plate is preferably arranged for movement along a plane which is central to the lock as shown in Fig. 35

40 1. At its forward end, the carrier is provided with flanges 27 which extend transversely thereto and contact the front wall 28 of the lock and the cover plate 29 thereof. Supported upon said carrier as by means 45 of a pin 30 is a movable member or bell crank 31 which is adapted for pivotal movement about said pin and along the face of the carrier. Said bell crank is provided with a pair of spaced pins 32 and 33 upon the former 50 of which a spring 34 is mounted, one end of which spring has co-operation with the pin 33, and the other end thereof with a pin 35 fixed upon the carrier, whereby a force is imparted to the bell crank tending to rotate 55 the same in a clockwise direction, looking at Fig. 2. The other arm of the bell crank is provided with means to engage a movable or rotary member such as a crank arm 36 or the like adjacent to the plate 29 whereby the bell 60 crank may be swung in counter clockwise direction about the pin 30. More specifically, said bell crank is provided with a lug 37 of substantially U form or the like, the open end of the U lying disposed to receive the 65 downwardly projecting lug 38 of the crank

arm 36. A similar crank arm 39 is provided adjacent to the wall 28 of the lock, arranged to engage a U member 40 or the like. The crank arm 36 is operated by means of the blade 41 which is turned by key operated mechanism in a conventional manner, while the crank 39 is rotated directly by means of the knob 14. The U 40 is positioned upon an opposite side of the carrier relatively to the U 37 and has suitable connection therewith as by means of a pin 42. The carrier plate may be provided with an arc-shaped slot 43 within which said pin is movable when the bell crank is operated, thus making for a rigid construction of the actuating mechanism. It will be observed that both the U 37 and the U 40 open in the same direction thus providing for the desired movement of the bell crank either by a key or the knob 14. The member 40 however is provided with an extension 44 which is adapted to abut against the circular flange portion of the crank 39, when the bell crank is retained by the spring in normal position either with the bolts projected or retracted. Abutment 50 is also provided between a shoulder 45 forming a part of the case and the extension 44 of the crank arm. In this way the bolts are retained against movement except in the usual manner by actuation of the bell crank 55 by one of the crank arms, thus preventing unintended movement of the bolt. To unlock the door, the abutting portion of the bell crank is sprung to a side of the lock by means of a crank arm, further rotation of said arm 60 operating to impart a force to the bell crank, which is in turn transmitted to said carrier by means of the pin 30 causing the carrier to move along the lock and to project or retract the bolts. If the latter occurs, abutment 65 takes place as shown in dot-dash lines in Fig. 3. The spring insures that the bell crank will be retained constantly in normal abutting relation. A lug or guide 46 is provided upon the bell crank in position to slidably abut 70 against the cover plate 29 and thus, in co-operation with the feet 26 to retain the carrier plate in central sliding position.

To guard against the possibility of a bolt 75 being cut by a saw inserted between the lock casing and the jamb piece, the bolt may be made of case hardened steel or its equivalent, or I may provide hardened steel re-enforcement means to co-operate with said bolt so as to lie in the path of the saw. More specifically, pins 47 which are case hardened or the like are inserted into each bolt 16 adjacent to the outer portions of the lock. Thus the bolt may be made of cheaper metal which, however, will be of sufficient strength and 80 toughness to withstand all stresses, while said pin renders the bolt saw-proof. It will be noted also that the inner or heel ends of the bolt members, in projected position, abut 85 squarely and directly against the forward 90

110 115 120 125 130 135

edge of the carrier and flanges 27 flush therewith. Hence the forward thrust of the actuator can by no means tend to cause the bearing 17 to spread the bolt members apart or in any other manner cause interference with the intended free sliding of the bolt in either direction.

It will thus be seen that as shown my invention comprises actuating means having a member or carrier movable in a straight line along the lock, means for actuating the same, and connecting means and specifically, a bell crank for making the rotation of the crank means effective to move said carrier as aforesaid, novel abutment means being provided which co-operate with the bell crank to retain the bolt against unintended movement. It will be noted also that the length of the bolt members and their manner of actuation provide for a considerable variation in clearance between the striking edge of the door and the jamb piece without interfering with the proper and reliable operation of the mechanism.

25 I claim:

1. In a lock, the combination with a bolt, of actuating means for operating said bolt, said actuating means comprising a carrier movable along the lock, a swinging member mounted upon said carrier, and a crank member for operating said swinging member, and having abutment therewith, said crank being connected to said swinging member to move said bolt, said swinging member being normally in abutment relation with said crank and out of abutment relation therewith when swung by said crank member in order to move the carrier, and said abutment relation operating to prevent movement of the carrier along the lock except when said swinging member is actuated as aforesaid.

2. In a lock, the combination with a bolt, of actuating means for operating said bolt, said actuating means comprising a carrier, a movable member borne by said carrier, and crank and abutment means within the lock co-operating with said movable member to move the same out of abutment relation and then to exert a force upon said member which in turn imparts said force to said carrier to move the same and hence the bolt into projected or retracted position, and guide means within the lock for causing said carrier to move in a predetermined line along the lock between its extreme positions, the lateral component of said force being taken up by said guide means.

3. In a lock, the combination with a bolt, of actuating means for operating said bolt comprising a carrier, a bell crank pivoted upon said carrier, resilient means co-operating therewith to retain said bell crank in constant normal position, a crank member for swinging said bell crank to cause said carrier to move along the lock to operate said bolt,

guide means for causing said carrier to move along a predetermined line of motion, and abutment means having abutment relation with said bell crank to retain the same against movement along the lock except when said bell crank is swung out of abutment relation by means of said crank member.

4. In a lock, the combination with a bolt, of actuating means therefor comprising a carrier movable along said lock, a movable member mounted upon said carrier, a crank arranged to engage said movable member to impart a force thereto to cause said carrier to move along the lock, means having abutment with said movable member when the bolt is projected and when it is retracted at the extreme limits of motion of said actuating means to prevent movement of said bolt except when said movable member is swung out of the path of said abutment means by said crank member, and means tending normally to retain said movable member in abutment relation.

5. In a lock, the combination with a bolt, of actuating means therefor comprising a carrier movable along said lock, a movable member mounted upon said carrier, said movable member comprising parts positioned upon opposite sides of the carrier, a plurality of cranks, one on each side of the carrier and adapted selectively to engage the movable member upon the respective sides of the carrier to impart a force thereto to cause said carrier to move along the lock, means having abutment with the movable member when the bolt is projected and when it is retracted at the extreme limits of motion of said actuating means to prevent movement of said bolt except when said member is swung out of the path of said abutment means by action of the cranks, and means tending normally to retain said movable member in abutment relation.

6. In a lock, the combination with a bolt, of actuating means therefor comprising carrier means to operate the bolt, means for causing the carrier to move along the lock, a movable member borne by the carrier means, abutment means co-operating with said movable member to prevent unintended movement of the carrier means, and means normally retaining said movable member in abutment relation, the means for causing the carrier to move along the lock being operative to cause said movable member to move out of abutment relation to permit the carrier to move along the lock to operate the bolt.

7. In a door lock of the character set forth, the combination with a casing and a jamb piece, of a bolt projectable from the casing into the jamb piece, an actuator for the bolt comprising a carrier and a bearing member projected forward from the main portion thereof, the bolt having bearing connection with the bearing member, the carrier being

provided also with means against which the inner end of the bolt has direct actuating co-operation, and means to move the actuator.

8. In a door lock, the combination with a casing for the door and a keeper for the jamb, of a bolt projectable from the casing into the keeper for engagement therewith, an actuator for the bolt comprising a plate-like carrier having an integral shank projecting from its forward edge, the bolt having tiltable co-operation with the front end of said shank, said carrier furthermore having a flat abutment member at its forward edge against which the inner end of the bolt squarely abuts when projected, and means to move the carrier along the casing and cause thereby the tilting movements of the bolt.

9. A lock, including a casing, a bolt retractable within said casing, a plate movable

to project said bolt and being formed with a slot, an arm movably carried by said plate, bolt-actuating means, and means carried by said arm and extending through said slot to be engaged by said actuating means.

10. A lock, including, in combination, a casing, a bolt retractable within said casing, a plate connected with and carrying said bolt, a crank pivoted to said plate, engagement elements secured to the outer end of said crank, and one of the same extending through an arcuate slot formed in said plate, and lock-actuating means associated with said casing and contactable with said engagement elements for exerting pressure upon said crank to shift said plate and project said bolt. 35

In testimony whereof I affix my signature.

FRANCIS J. DOWLING.
